GEORG KOCH, OF DARMSTADT, GERMANY, ASSIGNOR TO DR. ERNEST CADGENE AND OLAV BERG, BOTH OF PATERSON, NEW JERSEY.

METHOD OF WEAVING PILE FABRICS.

1,382,516.

Specification of Letters Patent. Patented June 21, 1921.

Application filed July 26, 1920. Serial No. 399,207.

To all whom it may concern:

Be it known that I, GEORG KOCH, a citizen of Germany, residing at F Heinrich-Fuhrstrasse, Darmstadt, Hessen, Germany, have 5 invented certain new and useful Improvements in Methods of Weaving Pile Fabrics, of which the following is a specification.

This invention relates to the art of weaving and particularly to the weaving of pile fabrics. The invention is an improved 10 method of weaving pile fabrics whereby a fabric may be produced that may be quite thin and also pliable and light in weight and yet have its weave compactly formed and 15 well adapted to resist stretching strains and its pile so disposed as to well "cover" the ground of the fabric, although the component threads may be few in number and need not be especially thick.

20 The drawing shows in the two figures longitudinal sectional views of two different forms of pile fabric capable of being formed by the improved method.

In Figure 1 *a* designates the aforesaid 25 tight warp, *b* a loose warp and *c* a pile warp. It is not indispensable, though it is preferable, that in the finished product the warp *a* should be straight, as shown: the terms "tight" and "loose" are herein used simply 30 to express that the warp *a* is held under greater tension during the weaving process than the warp *b* so that the crossing and binding of these two by filling and with reference to each other will exhaust more 35 yardage of the warp *b* than the warp *a* and warp *b* will be left sinuous, while warp *a* is left straight or at least less sinuous; the straighter the warp *a* is in the finished product the less susceptible will the fabric be to 40 stretch and so open up under stretching strains. Warp *c* is also looser than the warp *a*, that is, under less tension, and is preferably subject to means (not shown) to positively let off or feed warp each time a row 45 of pile loops is to be formed, according to the height of pile desired. *d* designates shots of weft or filling. At intervals, as 1, 1, 1, the warp *b* is made to cross and recross the warp *a*, a shot of filling *d* being 50 passed between the two warps between their points of crossing. These shots of filling are at the back of the fabric. Between each two intervals 1, 1 and at the other side of 55 the fabric four (it may be some higher even number) crossings of the warp *b* and pile

warp *c* take place and between each two such crossings a shot of filling *d* is passed.

In Fig. 1 there are an even number of crossings of the loose warps with respect to each other and the pile loops rise between 60 the middle two crossings of the warps *b* and *c*.

In Fig. 2 there are an odd number of crossings of the looser warps with respect to each other, and the pile loops rise between 65 the first and second; there are bindings, however, of them with respect to the tight warp by weft or filling at the other side of the tight warp, thus:

e is the tight warp, and *f* and *g* loose warps 70 (i. e., warps under less tension than the warp *e*). The warps *f* and *g* in this case both go to form pile loops, i. e., alternately, and may have means to positively let off or feed warp alternately to form the rows of pile 75 loops. *h* designates shots of filling. At intervals, as 2, 2, 2, the warps *f* *g* are first one and then the other made to cross and recross the warp *e*, a shot of filling *h* being each time passed between the two warps (*e*, 80 *f* or *e*, *g*) between their points of crossing. Between these intervals and at the other side of the fabric three crossings of the warps *f* and *g* take place, and between each two such crossings a shot of filling *h* is 85 passed.

In the forming of the pile loops a false warp *x* (see my Patent No. 1,305,373, to wit, the "filling supports" *n* referred to therein) is employed. This warp or equivalent extends from the back of the loom forward 90 and has free ends indicated at *y*, being extended past the fell of the fabric more or less forward, the fabric clearing the same as the weaving progresses and the take-up 95 means of the loom advances it. In Fig. 1, between each two intermediate points of crossing of the warps *b* and *c* with reference to each other the warps *c* and *x* are made to cross and recross each other, the filling *d* being introduced over the warp *x*. In Fig. 2, between two of the points of crossing of the warps *f* and *g* with reference to each other the warp *f* (or *g*) which rises from below warp *e* crosses and recrosses with respect to the warp *x*, the filling *h* being introduced over warp *x* in each instance. 100 105

All the crossings of warps are effected by harness, and it will be preferable to have 110

the harness move the warps α in the forming of the sheds in which they are involved.

The shots of filling may be left in the pile loops 3, Fig. 1, or 4, Fig. 2, or if the pile loops are cut to leave tufts they may be removed.

In any event, the fabric produced is one which is characterized by little capability to stretch longitudinally of the warp because one warp exists therein more or less entirely without deflection; and it is possible in beating up to pack the material formed by the looser warps and weft or filling tightly together, thus to form a closely woven or compact fabric. That is to say, the value of the fixed or false warp α is that it serves not merely in the forming of the pile by supporting shots of the filling but in preserving the compactness of the fabric as determined by the reed in beating up: thus, as a matter of fact the farther the warp α projects forward, and consequently the more extensive the grip of the fabric on this warp, the more compact will the fabric be. Having thus a medium to preserve a certain degree of compactness attained by the reed, I form my fabric, not as shown in my hereinbefore mentioned patent, so that all the shots of filling except those in the pile loops are in the same plane and so that each of the ground warps becomes sinuous and so is capable of allowing the fabric to stretch, but with one warp tight and with the most of the shots of filling above this tight warp, such tight warp making the fabric non-stretchable and the specified arrangement of the filling, with the interweaving of the other or looser warps therewith, resulting in a massing of threads above the tight warp that increases and renders even more permanent the compactness of the fabric as a whole as well as brings the pile itself into

closer and more compact disposition than otherwise, the resulting product being a fabric which may be quite thin and pliable and yet is strong, rich, and uniform in texture and in which the pile so completely "covers" that, though the pile be uncut, the body or ground of the fabric will not be revealed between the rows of pile loops except the fabric be bent quite sharply in the transverse direction.

It is new in weaving, so far as I am aware, to interweave warps and filling between a tighter warp and a false warp having free ends, and at intervals bind by filling one of the first-named warps to the tighter warp and at intervals also bind by filling one of the first-named warps to the false warp, advancing the first-named and tight warps in the direction in which the free ends of the false warp project while holding the latter against advance.

Having thus fully described my invention, what I claim as new and desire to secure by Letters Patent is:—

The herein described method of weaving a pile fabric which consists in at intervals crossing through a tight warp, around filling at one side thereof and then back through the tight warp one of two other and less tight warps, and, between each two such intervals and at the other side of the tight warp, crossing said less tight warps three or more times with respect to each other and also one of them through a false warp having free ends, around filling and back through said false warp, all while simultaneously advancing the tight and less tight warps relatively to the false warp in the direction in which the free ends of the latter project.

In testimony whereof I affix my signature.

GEORG KOCH.
